COMBINED MANUAL SWITCH AND FUSE
BLOCK

Sylvanus C. Shipley and Benjamin Cyr, Minneapolis, Minn., assignors to Minneapolis-Honeywell Regulator Company, Minneapolis, Minn., a corporation of Delaware

Application July 22, 1938, Serial No. 220,718

18 Claims. (Cl. 200—114)

This invention is directed to the combination of a manually operated switching device mounted on the same base as the receptacle for one or more fuses, the same being assembled as a unit.

It is an object of this invention to provide a novel means of assembling a plurality of manual switches and a plurality of fuse sockets connected in series therewith, as a unit.

A further object is to provide a combined manual switch and fuse block in which one of the stationary contacts of the manual switch forms a holding means for a fuse socket.

A further object is to provide a novel means for releasably maintaining the operating handle and shaft of a rotating blade type of switch in assembled relation, said means comprising a biasing spring and a metal clip which cooperates with the handle.

A still further object is to provide a two part switch block in which a key is associated with the operating shaft for the switches for locking the two parts of the block together.

A further object of this invention is to provide a holder for a fuse of the cartridge type which may in turn be screwed into one of the sockets of the fuse block.

Where the switch and fuse block unit is being used in a circuit which handles 220 volts or more, it is desirable to use fuses of the cartridge type rather than of the plug type. In order that the same fuse block may be used in each case, a holder for the cartridge type of fuse is provided which may screw into the sockets of the fuse block.

A still further object of this invention is to provide interchangeable center contacts for the fuse sockets, the contacts being so designed that with one of them only the plug type of fuse may be placed in the socket to close the circuit, and with the other, only the cartridge type fuse holder may be placed in the socket to close the circuit.

Another object is to provide a novel construction for the holder for the cartridge fuse.

These and other objects will readily become apparent as the following specification is read in the light of the accompanying drawings, in which—

Figure 1 is a side elevation of the device with the switch contacts shown in open position;

Figure 2 is another side elevation with the parts in the same position, looking at the opposite side from that of Figure 1;

Figure 3 is an enlarged plan view of the base with the cover and rotatable switch blades removed;

Figure 4 is a section taken through both the base and the cover along the line 4—4 of Figure 3;

Figure 5 is a section also taken through both the base and cover and along the line 5—5 of Figure 3;

Figure 6 shows a section taken through the holder for the cartridge type fuse along the line 6—6 of Figure 7, showing also the fuse socket in section, and the modified form of central contact, and

Figure 7 shows a front elevation of the fuse holder.

The two part switch block which is indicated generally at 10 is comprised of a base 11 and a cover 12 for the base. The base 11 is provided with two vertical holes therethrough 13 and 14. An L-shaped metallic member 15 is frictionally held in the hole 13 by means of a prong or lip 16, better shown in Figure 3. The upper end of the member 15 is bent over as shown at 17 to form a flat contact surface and the lower end of the member 15 extends through the base to form a terminal for electrical connection with an external circuit. The hole 14 is provided with a second metallic member 18 which is identical with the member 15 only it is turned 180 degrees with respect thereto. Member 18 is frictionally retained in the hole 14 by means of the prong 29.

Surrounding the upper portion of the member 15 is a projection on the base 11 which is of a square form and is indicated at 19. A metallic socket 20 is provided which has a U-shaped cut-away portion at its lower extremity as indicated at 21 which is adapted to seat over the projection 19 on the base 11. A contact member 22 shown in Figure 3 is provided with a square hole, as indicated at 23, which is adapted to be inserted within the lower part of the socket 20 through the cut-away portion and which is adapted to seat over the projection 19 of the base. The member 22 has a short tail 24 which extends outside of the socket 20 and is for a purpose to be later described. The opposite end of the member 22 is bent upwardly, as shown at 25, and is in the form of an arc. The arcuate formation of this contact may be more clearly seen with reference to Figure 2.

Surrounding the contact member 18 is a second projection 26 on the base 11 and a socket 27 and contact member 28 are seated over projection 26 in exactly the same manner as the socket 20 and member 22 are seated over the projection 19.

It will be noted, however, with reference to Figure 3 that the contact member 28 is turned

180 degrees with respect to the contact member 22. The base 11 is provided at its opposite sides with two arcuate slots 30 and 31 through which a rotatable switch blade to be later described is adapted to move. A third hole 32 extends through the base 11 and into which is inserted one end of a contact member 33 which is of a zig-zag shape, as indicated in Figure 3. As shown in Figure 5, the end of the contact 33 which extends through the hole 32 is in the form of a terminal to which an external electric circuit may be connected. The other end of the member 33 is in the form of a flat contact, as indicated at 34 in Figure 1. The connecting portion 35 is seated in a slot 36 in the base 11. Another hole 37 is provided in the base 11 with another contact member 38 of identical shape with the contact 33 and which is mounted in the same manner but on the opposite side of the base 11 and turned 180 degrees with respect to the contact 33. The member 38 is also provided with a contact surface 39, as seen more clearly in Figure 2. The contact surface 39 is placed diagonally opposite the arcuate contact surface 25 on one end of the member 22 and the two surfaces 39 and 25 cooperate to form the two stationary contacts of an electric switch, as shown in Figure 2, and in Figure 1 it is seen that the two contact surfaces 34 and 40 are located diagonally opposite to each other to form the stationary contacts of a second switch.

The cover 12 is provided with two vertical holes 41 and 42 which are adapted to house the sockets 20 and 21 when the cover is in position on the base 11. It will be noted with reference to Figure 3 that the base 11 is provided with two projections 43 which cooperate with two holes (not shown) in the cover 12 for properly positioning it on the base 11. It will be noted that as the cover 12 is placed on the base 11 it engages the contact members 35 and 38 to hold them properly in the slots in which they are mounted and that it also engages the contact members 22 and 24 to firmly hold them in their proper positions over the projections 19 and 26 on the base. It will be noted further that the contact members 22 and 28 engage the lower portion of the sockets 20 and 21 so that the sockets themselves are also held in position by the cover 12. A plug type fuse 29 has been shown in Figure 4 screwed into the socket 27.

The cover 12 is provided with a transverse hole 45 which is tapered slightly toward the center from each end, as shown in Figure 5. Rotatably mounted in this hole is a shaft of hexagonal cross-section 46. On the end 47 of the shaft 46 is mounted a sleeve 48 having a hexagonal hole 44 therethrough so that it is longitudinally slidable on the shaft 46 but is non-rotatable with respect thereto. The sleeve 48 is provided with a circular flange 49 and a hexagonally shaped shoulder 50 on which is mounted a contact blade 51 having two arms extending in opposite directions, as shown in Figure 1, the connecting portion 52 between the two arms being considerably wider than the arms and having a hexagonal hole therethrough so that the entire blade 51 may seat on the hexagonal shoulder 50 of the sleeve 48 and will be rotated thereby upon rotation of the shaft 46. An operating handle 55 is provided at one end with a hexagonal hole 54 which is adapted to fit over the end 47 of the shaft 46 and is retained thereon by means of a metal clip 56 which engages a groove 57 in the shaft 46 and which has a bent over portion 58 which is inserted through a hole in the handle 75

55 and which extends longitudinally of the shaft 46. The purpose of the clip 56 is to maintain the handle 55 on the shaft 46 and in engagement with the sleeve 48.

Mounted on the opposite end 60 of the shaft 46 is a second sleeve 61 of identical formation with the sleeve 48 and in the same manner a switch arm 62 is mounted on the sleeve 61 so as to be rotated thereby on rotation of the shaft 46. The sleeve 61 is provided with a chamber 63 in which is located a compression spring 64. A second metallic clip 65 identical with the clip 56 engages groove 66 in the shaft 46 to confine the compression spring 64 between the inner end of the chamber 63 and the metal clip 65. The spring 64 will tend to pull the shaft 46 towards the right, as seen in Figure 5, which movement will be limited by the engagement of the handle 55 with the sleeve 48. The function of the spring 64 is therefore to maintain the operating handle, the two sleeves, and switch blades and the operating shaft in assembled relation.

The cover 12 is provided with a cut-away portion at each side of circular formation, as disclosed at 70 in Figure 1 and 71 in Figure 2, which register with slots 30 and 31 in the base 11 to form a path for the switch arms of the blades 51 and 62 as they are rotated by the handle 55.

The base 11 is provided with a slot 72 and the cover 12 is provided with a slot 73, the slots 72 and 73 registering with each other when the cover is properly placed on the base. It will be noted with reference to Figure 4 that the slot 72 in the base 11 is provided with a pair of shoulders 74 against which the shoulders 75 of a key 76 are adapted to seat. The key 76 is inserted into the slots 72 and 73 as far as it will go, at which time a hole 77 in its upper end will register with the hole 45 through the cover 12. Referring to Figure 5, it will be seen that when the shaft 46 is positioned in the cover 12, it will extend also through the hole 77 of the key 76 and when the parts are so assembled the key 76 will maintain the cover 12 and the base 11 in assembled relation due to the coaction of the shoulder 75 with the corresponding shoulder 74 on the base 11.

In assembling this instrument, the contact members 15 and 18 are first inserted into their respective holes 13 and 14 and forced downwardly until their upper ends are in engagement with the projections 19 and 26 on the base 11. When this has been done, the contact members 35 and 38 are next properly inserted in the base 11 as indicated in Figure 3 so that their lower ends will protrude downwardly through the base to form the circuit terminals as described above. The socket members 20 and 21 are next passed over the projections 19 and 26 and the contact members 22 and 28 are inserted through the cut-away portions in the socket members and are also placed over the projections 19 and 26. The cover 12 is next placed over the sockets and the base 11 and properly positioned thereon by means of projections 43 which will extend into holes 55 in the cover 12. The key 76 is next inserted through the slots 72 and 73 until the hole 77 registers with the transverse hole 45 through the cover 12. At this time, the shaft 46 may be inserted through the hole 45 and the hole 77 of the key 76. The rotatable switch blade 62 may then be mounted on the sleeve 61 and the two mounted on the end 60 of the shaft 46. Spring 64 is then placed over the end of the shaft 46 and into chamber 63 of the sleeve 61. The metal clip 65 is then placed in the groove 66 on the

end 60 of the shaft 46 and the spring 64 thus confined within chamber 63. Next the switch blade 51 is placed on the sleeve 48 and the two mounted on the other end of the shaft 46. The operating handle 55 is placed on the end of the shaft and it will be seen that before the metal clip 56 can be inserted in the groove 57 and the end 58 inserted through the hole in the handle 55, the shaft 46 must be moved slightly toward the left by compressing spring 64. This will permit the clip 56 to be properly mounted with respect to the shaft and handle 55 and when the shaft is released the spring 64 will move it towards the right, at which time the contact structure will be in assembled relation.

The circuits through this combined manual switch and fuse block may be very easily traced by referring to Figure 3. The end 33 of the contact 35 as described above forms one terminal to which an external circuit may be connected. The end 33 is electrically connected to the contact surface 34 and when the switch blade 51 is in closed circuit position, the contact surface 34 will be electrically connected with the contact surface 40 which is in metallic contact with the socket 27 in which will be screwed a fuse which will connect the socket 27 with the center contact 18 which forms the other terminal to be connected in the external circuit. The circuit therefore passes through the manual switch 51 and the fuse in socket 27 in series. In like manner, the other circuit will pass through the contact member 38, the switch blade 62, the contact 22, socket 20, the fuse which will be screwed therein and thence to the terminal 15. The two switches and fuses disclosed may either be placed in two separate circuits or the pair of them may be located in the same circuit if desired.

The operation of the switch mechanism is believed to be obvious in view of the above description. In Figure 1, the operating handle is shown in its raised position at which time the switch blade 51 will be in open circuit position. Figure 2 shows the operating handle in the same position but looks at the other end of the device showing the switch blade 62 in open circuit position. Referring back to Figure 1, if the operating handle 55 is rotated in a counter-clockwise direction through an angle of 90 degrees, the switch blade 51 will be rotated so that it will make contact with the contact surface 34 and contact surface 40 and electrically connect them. At the same time, the switch blade 62 will have been rotated through an angle of 90 degrees in a clockwise direction as viewed in Figure 2 and will have electrically connected the contact surface 39 with the contact surface 25. It will thus be seen that the two switches are operated in unison and they are both opened or both closed at the same time.

The above description has been directed to a fuse socket for accommodating a fuse of the plug type, which is the type of fuse used on circuits carrying around 110 volts. Where it is desired to use the present combined manual switch and fuse block in a circuit carrying 220 volts, it will be necessary to use fuses of the cartridge type and it is obvious that the present fuse block is not adapted to receive cartridge type fuses unless some special type of fuse holder is provided. Such a fuse holder will now be described.

Referring to Figures 6 and 7, reference numeral 90 indicates a unitary piece of insulating material comprising a base portion 91 and an extending supporting portion 92. The base portion 75

91 is exteriorly threaded to receive a cylindrical conducting strip 93 which is screw-threaded to it and adapted to be received in one of the sockets of the fuse plug. A U shaped clip is indicated at 94 having a conducting strip 95 integrally connected therewith, said conducting strip being inserted through a slot 96 in the base and a slot 97 in the support 92. The strip 95 is permanently electrically connected to the conductor 93 by means of solder 98. A thin strip of insulating material 99 is placed over the strip 95 so that a second U shaped metallic clip 100 which seats on the base 91 is insulated with respect to the clip 94. The bottom portion of clip 100 is provided with a screw-threaded hole 101. The base 91 is provided with a chamber 102 at its outer end and at the inner end of the chamber is a hole 103 which registers with the hole 101 but which is of a slightly larger size. A screw 104 is inserted through the hole 103 and engages the screw threads in the hole 101 of the clip 100 and is tightened therein by means of the head 105 compressing a spring washer 106 against the base 91. It will be seen that the screw 104 holding the clip 100 in position also maintains the insulation 99 as well as the clip 94 and strip 95 in assembled relation with the body 92.

The clips 94 and 100 are adapted to receive the metallic terminals 110 and 111 of the cartridge type fuse 112 illustrated in Figure 6. The fuse 112 may be mounted in the holder 90 after which the whole assembly may be screwed as a unit into one of the sockets of the fuse block, for example the socket 20.

It is a purpose of this invention to provide a single fuse block for use in either a low voltage or a high voltage system but to provide a means for preventing the use of a plug type fuse when the fuse block is intended for use in a high voltage system, and on the other hand to prevent the use of a cartridge type fuse when the fuse block is intended for use in a low voltage system. This is accomplished by using a different type of central contact for the fuse socket for each of the two circuits and to design the special fuse holder so that it will cooperate with only one of the two types of central contacts. Where the fuse block is to be used on a low voltage system, the short flat central contact is used, such as is indicated at 18 in Figure 4. As shown in this figure, the plug type fuse may be inserted in the socket 27 to close the circuit between the socket 27 and the central contact 18. If the special fuse holder 90 were screwed into the socket 27, it will be seen that the contact 18 would not extend up into the chamber 102 in the base 91 so that the circuit would not be completed from the socket 27 to the contact 18. Therefore it will be impossible to use a cartridge type fuse with the short central contact 18.

Where it is desired to use the switch block in a high voltage circuit, a long central contact such as is indicated at 115 in Figure 6 is used, it being noted that the upper end 116 of the contact 115 is U shaped and extends nearly up to the top of the socket 20 but that it is mounted in the hole 13 and cooperates with the base 11 in the same manner as the contact 15 in Figure 4. Now when the fuse holder 90 is screwed into the socket 20, the contact 115 will engage the head 105 of the screw 104 so that a circuit will be completed from the contact 115, screw 104, clip 100, through the fuse 112 to the clip 94, conducting strip 95, and back to the socket 20. It will be noted that the contact 115 extends so high up into the socket 20

that it is impossible to screw a plug type fuse in the socket such as is indicated at 28 in Figure 4, into the socket. This arrangement makes it impossible to make a mistake and insert the wrong type of fuse into the fuse block.

One of the important features in this invention is the fact that in this unit there are no permanent connections made. To take the entire structure apart, it is necessary only to press inwardly on the end 68 of the shaft 46, thus compressing the spring 64 and slide the operating arm 55 slightly toward the right, as viewed in Figure 5, after which the metallic clip 56 may be removed as well as the operating handle 55 and then the entire shaft may be pulled out towards the right. After this has been done, the entire structure can immediately be easily disassembled.

It will be noted that the operating handle 55 is provided with a bent over portion 80 on which appears the word "off" and that the flattened surface 81 is provided with the word "on." This is so that when the present unit is mounted in a casing with only the handle protruding therefrom it can be determined by looking downwardly on the device as viewed in Figure 1 whether the switch is open or closed. Four slots 82 are provided in the base 11 for the purpose of mounting a thin strip of insulating material if it is desired to protect the casing in which the unit is to be mounted from sparks which might be caused by arcing at the switch contacts.

Certain modifications of this invention may occur to those who are skilled in the art, and it is therefore understood that we are to be limited by the scope of the appended claims and not by the specific embodiment disclosed.

We claim as our invention:

1. In combination, a base, a switch comprising a pair of stationary contact members and a rotatable switch blade mounted on said base, means for rotating said blade, a fuse socket including a shell and a center terminal electrically insulated from one another mounted in said base, one of said contact members engaging the shell of said socket to electrically connect it with said switch and also to maintain the entire socket on said base.

2. In combination, a base, a switch comprising a pair of stationary contact members and a rotatable switch blade mounted on said base, means for rotating said blade, a fuse socket mounted in said base, one of said contact members engaging said socket to electrically connect it with said switch and also to maintain it on said base, the other of said contact members extending downwardly through said base to form a terminal, and a second terminal extending upwardly through said base to cooperate with said socket.

3. A switch mechanism comprising in combination, a base, a pair of spaced stationary contacts mounted on said base, said base having a hole between said contacts, a rotatable shaft extending through said hole, a switch blade mounted on said shaft and rotatable thereby into and out of engagement with said stationary contacts, an operating handle mounted on said shaft, a clip on said shaft preventing removal of said handle unless said shaft is moved longitudinally, and a spring resisting longitudinal movement of said shaft.

4. A switch mechanism comprising in combination, a base, a pair of spaced stationary con-

tacts mounted on said base, said base having a hole between said contacts, a rotatable shaft extending through said hole, a switch blade mounted on said shaft and rotatable thereby into and out of engagement with said stationary contacts, an operating handle mounted on one end of said shaft, a spring mounted on the other end of said shaft, a spring retainer cooperating with the outer end of said spring, a bearing member for the inner end of said spring, said spring tending to pull said shaft through said hole, and a clip cooperating with said handle to prevent said shaft from passing through said hole, a bearing member, said handle being held against said bearing member by said spring, said clip being incapable of removal unless said shaft is moved slightly against the action of said spring.

5. In combination, a base, a first pair of stationary switch contacts mounted on one side of said base, a second pair of stationary contacts mounted on the opposite side of said base, said base having a hole extending therethrough from said one side to the other, a shaft rotatably mounted in said hole and extending out slightly beyond said base on each side, a first sleeve slidably mounted on one end of said shaft, a first contact blade mounted on said sleeve for cooperation with one pair of stationary contacts, another sleeve and contact blade mounted on the other end of said shaft, both sleeves and contact blades being adapted to rotate with said shaft, an operating handle fixed on said other end of said shaft, and resilient means on said one end of said shaft holding the sleeves, contact blades, operating handle, and shaft in assembled relation.

6. In combination, a base, a first pair of stationary switch contacts mounted on one side of said base, a second pair of stationary contacts mounted on the opposite side of said base, said base having a hole extending therethrough from said one side to the other, a shaft rotatably mounted in said hole and extending out slightly beyond said base on each side, a first sleeve slidably mounted on one end of said shaft, a first contact blade mounted on said sleeve for cooperation with one pair of stationary contacts, another sleeve and contact blade mounted on the other end of said shaft, both sleeves and contact blades being adapted to rotate with said shaft, an operating handle fixed on said other end of said shaft, a first metal clip removably mounted on said shaft and extending inwardly through a hole in said handle for preventing said handle from being forced off the end of said shaft, a recess in the outer end of said first sleeve, a second metal clip mounted on said shaft, and a compression spring confined in said recess by means of said second clip.

7. In combination, a base, a first pair of stationary switch contacts mounted on one side of said base, a second pair of stationary contacts mounted on the opposite side of said base, said base having a hole extending therethrough from said one side to the other, a shaft rotatably mounted in said hole and extending out slightly beyond said base on each side, a first sleeve slidably mounted on one end of said shaft, a first contact blade mounted on said sleeve for cooperation with one pair of stationary contacts, another sleeve and contact blade mounted on the other end of said shaft, both sleeves and contact blades being adapted to rotate with said shaft, an operating handle fixed on said other end of said shaft, a metal clip removably mounted on said

shaft extending inwardly through a hole in said handle whereby said handle must first be moved inwardly of said shaft before said clip can be removed, and resilient means on said one end of said shaft for resisting such relative movement of the handle and clip whereby said parts are releasably held in assembled relation.

8. A device of the character described comprising in combination, a base, a first metallic member extending through said base and forming a first stationary switch contact and also a terminal for connection with an outside circuit, a fuse socket mounted on said base, a second metallic member forming a second stationary switch contact and also engaging said socket to maintain it in position, a rotatably mounted switch blade for electrically connecting said stationary contacts, and a third metallic member extending through said base to form a second terminal for connection with the outside circuit, the other end being within the socket to complete the circuit when a fuse is screwed into said socket.

9. A device of the character described comprising in combination, a base, a first metallic member extending through said base and forming a first stationary switch contact and also a terminal for connection with an outside circuit, a fuse socket mounted on said base, a second metallic member forming a second stationary switch contact and also engaging said socket to maintain it in position, a rotatably mounted switch blade for electrically connecting said stationary contacts, a third metallic member extending through said base to form a second terminal for connection with the outside circuit, the other end being within the socket to complete the circuit when a fuse is screwed into said socket, a cover for said base, said cover having a hole adapted to accommodate the fuse socket, said cover clamping said first and second metallic members and holding them in place, and means for connecting said cover to the base.

10. A device of the character described comprising in combination, a base, a first metallic member extending through said base and forming a first stationary switch contact and also a terminal for connection with an outside circuit, a fuse socket mounted on said base, a second metallic member forming a second stationary switch contact and also engaging said socket to maintain it in position, a rotatably mounted switch blade for electrically connecting said stationary contacts, a third metallic member extending through said base to form a second terminal for connecting with the outside circuit, the other end being within the socket to complete the circuit when a fuse is screwed into said socket, a cover for said base, said cover having a chamber adapted to accommodate the fuse socket, said cover having a transverse hole therethrough, a shaft in said hole, said switch blade being mounted for rotation by said shaft, and means engaged by said shaft when it is in said hole for maintaining said base and cover in assembled relationship.

11. A device of the character described comprising in combination, a base, a first metallic member extending through said base and forming a first stationary switch contact and also a terminal for connection with an outside circuit, a fuse socket mounted on said base, a second metallic member forming a second stationary switch contact and also engaging said socket to maintain it in position, a rotatably mounted switch blade for electrically connecting said stationary

contacts, a third metallic member extending through said base to form a second terminal for connection with the outside circuit, the other end being within the socket to complete the circuit when a fuse is screwed into said socket, a cover for said base, said cover having a chamber adapted to accommodate the fuse socket, said cover having a transverse hole therethrough, a shaft in said hole, said switch blade being mounted for rotation by said shaft, and means engaged by said shaft when it is in said hole for maintaining said base and cover in assembled relationship, said means comprising a key, registering slots in said base and cover, said key being positioned in said slots and extending through said base and into said cover, a hole in said key which registers with the transverse hole through said cover, and a shoulder on said key holding said base in engagement with said cover.

12. In combination, a two part switch block comprising a base and a cover, a pair of stationary contacts mounted on said base, a shaft rotatably mounted in said cover, a switch blade rotated by said shaft into and out of cooperation with said stationary contacts, and a key, said shaft engaging said key to lock said base and cover together.

13. In combination, a two part switch block comprising a base and a cover, a pair of stationary contacts mounted on one side of said base, a second pair of stationary contacts mounted on the other side of said base, a pair of fuse sockets mounted on said base, a pair of chambers in said cover for housing said sockets, said cover having a transverse hole therethrough, a shaft rotatably mounted in said hole, two switch blades mounted on said shaft, one for each pair of stationary contacts, an operating handle for said shaft, and means engaged by said shaft for holding said base and cover together.

14. A combined manual switch and fuse block comprising in combination, a base, said base having two holes, two metallic members each frictionally retained in one of the holes, two fuse sockets, each socket being mounted on said base around one of said members, two stationary contacts, each contact engaging one of said sockets to hold it in proper position, two additional holes in said base, two additional contacts each extending through a hole in said base, a cover for said base having two chambers each of which houses one of the sockets, said cover having a transverse hole therethrough, a shaft loosely mounted in said last named hole, two contact blades removably mounted on said shaft for rotation thereby, each blade cooperating with two of said stationary contacts, registering slots in said base and cover, a key in said slots, a shoulder on said key engaging said base, said key having a hole registering with the transverse hole through said cover and through which said shaft extends whereby when said shaft is in place said cover and base are locked together clamping said first two stationary contacts and said sockets in place, means for preventing removal of said shaft from said hole comprising a metal clip, and resilient means for locking said metal clip in place.

15. A fuse holder comprising in combination a support, a socket mounted in said support, a central contact extending upwardly through said socket for over half its height rendering the insertion of an ordinary plug type fuse impossible, a member having a screw-threaded base adapted to be screwed into said socket, a chamber in said base for housing said central contact, means on

said member for removably supporting a cartridge type fuse, and means on said member electrically connecting said central contact and socket to said fuse holding means when said member is screwed into said socket.

16. A holder for a cartridge type fuse comprising in combination, a base of insulating material, a screw-threaded conducting member surrounding said base, an extending support integral with said base, a spring clip at the distal end of said support, said clip having a conducting strip connected electrically to said screw-threaded conducting member, a second spring clip at the near end of said support, insulating means separating said second clip from said strip, and a screw extending through said base and engaging said second clip to hold it against said insulating means whereby it also holds said strip and first clip in position, said clip being adapted to hold a fuse of the cartridge type and said screw

5 forming an electrical contact for said fuse holder.

17. In combination, a base, a switch including stationary contact means and a rotatable switch blade mounted on said base, means for rotating said blade, a fuse socket including a shell and a center terminal electrically insulated from one another mounted in said base, said stationary contact means engaging the shell of said socket to electrically connect it with said switch and also to maintain the entire socket on said base.

10 15 18. In combination, a two part switch block comprising a base and a cover, stationary contact means mounted on said base, a shaft rotatably mounted in said cover, a switch blade rotated by said shaft into and out of cooperation with said stationary contact means, and a key, said shaft engaging said key to lock said base and said cover together.
